UNITED STATES PATENT OFFICE.

FLORENCE BROWNING BIGGS, OF NEW YORK, N. Y.

HELMET-CAP.

1,275,838.

Specification of Letters Patent. Patented Aug. 13, 1918.

Application filed February 9, 1918. Serial No. 218,301.

To all whom it may concern:

Be it known that I, FLORENCE B. BIGGS, a citizen of the United States, and a resident of the city of New York, borough of Manhattan, in the county and State of New York, have invented a new and Improved Helmet-Cap, of which the following is a full, clear, and exact description.

Among the principal objects which the present invention has in view are: to provide an article of wear of the character mentioned adapted for arrangement in various forms; to facilitate the arrangement of the same to the head of the wearer; to reduce the cost of construction; and to produce a neat and presentable article when worn on the head.

Drawings.

Figure 1 is a view showing the cap from the front thereof in service and in folded position;

Fig. 2 is a similar view, the view being taken from the rear;

Fig. 3 is a view taken from the front of the cap, showing the same arranged for covering and protecting the head, neck, face and throat of the wearer;

Fig. 4 is a similar view as seen from the rear;

Fig. 5 is a view of the blank from which the body of the cap is constructed;

Fig. 6 is a view of the blank forming the tip of the cap.

Description.

As seen in the drawings and particularly in Figs. 5 and 6 thereof, the cap is constructed from two pieces of material, the piece shown in Fig. 5 being provided with oppositely-disposed extensions 11, the ends of which are joined by a seam to form the side crown 12. The upper edge of the side crown is joined by a seam to the tip 13. These two operations constitute what might be termed the manual labor required in assembling the two parts to form the herein-described cap.

The blanks shown in Figs. 5 and 6 are constructed from suitable material, and preferably from a woven fur-surfaced material which has a large amount of resiliency and which does not ravel. As an instance of the desired material, that known in the trade as "Kosw Cloth" is referred to. When using material of this character, the

blanks are cut out and delivered to the person assembling without further manipulation.

Referring to Fig. 5 of the drawings, it will be seen that the blank provides throat latches or convert straps 14 and 15. When worn, the strap 15 is outermost and is used as a securing element for fastening the cap in the various positions shown in the drawings. To this end, the strap 15 has a loop 16 formed thereon. This loop is preferably constructed from metal. It is obvious, however, that other materials and forms of loops may be employed. For coöoperating with the loop 16, two buttons 17 and 18 are secured to the body or apron 19. As at present constructed, there are employed only two buttons. It is obvious, however, that should occasion arise, three or more such buttons may be provided.

When the loop 16 is constructed of metal, a novel method of preparing the relatively yielding material from which the strap 15 is formed, is shown in the drawings at Fig. 5, where a non-resilient tab 20 is preliminarily sewed to the end of the blank. After the tab 20 is secured in position, the tab is passed through the eye of the loop 16 and the said tab and its lining are sewed permanently in position to the adjacent portion of the strap 15. With the securing of the loop 16 in position, the cap is completed and ready for service.

It will be understood that the cap may be worn in many positions to serve a variety of purposes. As shown in Figs. 1 and 2 of the drawings, the cap is folded with the apron 19 raised, and the straps 14 and 15 folded around the crown 12, the strap 15 coming to the outer side and the loop 16 being secured to the button 17 as seen in Fig. 2 of the drawings. In this position, the ears, back of the head and neck of the wearer are exposed.

When it is desired to cover the back of the head, ears and neck, this may be accomplished by dropping the apron 19 to the lowered position shown in Figs. 3 and 4 of the drawings. In this position, the ears, back of the head, and throat of the wearer are covered.

It is evident that by arranging the strap 14, the face as well as the throat of the wearer may be protected the width of the strap 15, permitting the same to be passed over the face to cover, if desired, the nose,

as well as cheeks, and mouth of the wearer. In adjusting the cap for service, it will be understood that the strap 15 is passed around the head of the wearer to the outside of the strap 14, and the loop 16 at the end thereof is made fast or secured to the button 18, thus drawing the throat latch close to the throat.

10

Claim.

15 A cap as characterized comprising a tip; a side crown having an apron and throat extensions at the bottom of said apron, said side crown, apron and throat extensions being integrally formed, one of said exten-

sions being shortened to overlie the chin of a wearer, the other extension being elongated to overlie the first-mentioned extension to hold the same in service position, and to cover the throat and back of the neck; 20 means for securing the last-mentioned extension in position to contract the extension upon the neck of the wearer, said means embodying a loop formed at the end of said last-mentioned extension; and a fastening 25 member disposed at the rear of said side crown.

LORENCE BROWNING BIGGS.
